UNITED STATES PATENT OFFICE

2,469,943

HORIZONTAL ROTARY SCALPER

Archie Axell, Minneapolis, Minn., assignor to
 Haaky Manufacturing Company, St. Paul,
 Minn., a corporation of Minnesota

Application December 9, 1944, Serial No. 567,372

1 Claim. (Cl. 209—288)

1

My invention relates to an improvement in horizontal rotary scalper wherein it is desired to provide an effective means of removing foreign particles from grain to be cleaned.

When grain is delivered to a mill or the like it often contains a great many impurities. These impurities range from pieces of metal, wood, and stones to various types of foliage and the like. Many of these impurities might prove extremely detrimental to the grain separating mechanism should they be permitted to pass with the grain into the separators. It is the main purpose of the present scalper to receive grain containing these large foreign particles and to separate the grain from the particles.

A feature of the present invention resides in the provision of a rotary screen mounted upon a horizontal axis against which the entering grain is permitted to flow. Rotation of the screen tends to carry the particles of foreign material over the top of the screen and to deposit the same in a suitable passage. The smaller particles of grain are permitted to pass through the screen and are thus transferred to a different chute or receptacle, thus completing the separation.

A feature of the present invention resides in the fact that the foreign material in the grain is carried over the top of the screen by frictional engagement with the screen. As a result it is almost impossible for small particles such as kernels of grain or the like to be carried over the top of the screen and deposited with the foreign matter found in the grain.

A feature of the present invention lies in the use of an outwardly indented screen having apertures in the indentations off-set from the center thereof. These indentations form outwardly extending projections on the screen which assist in the conveyance of larger particles of foreign matter over the top of the screen.

A further feature of the present invention lies in the method of withdrawing dust from the machine casing by suction. During the scalping process a certain amount of dust is created. Thus dust may be removed by subjecting the casing to the action of suction. While no aspiration of the grain, as it is commonly known, takes place, no dust or dirt exudes from the machine because of this suction connection to the casing.

A further feature of the present invention lies in the provision of an adjustable feed which regulates the flow of grain into the scalper, depending upon the speed with which the particular grain being scalped may pass through the apparatus. It is desirable to regulate the intake

2

of grain as by building up a deep well of grain adjacent the screen the effectiveness of the scalping operation is decreased.

A further feature of the present invention lies in providing a substantially horizontal shelf adjacent the screen upon which the enclosing grain is fed. This shelf forms a pocket of predetermined width adjacent the screen upon which grain may drop. Tests have shown that when a grain shelf is provided of the type described the action is greatly superior to a somewhat similar construction in which the grain is fed against the screen in a wedge shaped formation. The construction embodying the horizontal shelf seems to permit some of the weight of the enclosing grain to be supported by the shelf so that there is no great pressure forcing the grain against the surface of the cylinder.

These and other objects and novel features 20 of my invention will be more clearly and fully set forth in the following specification and claim.

In the drawings forming a part of my specification:

Figure 1 is a vertical section through my 25 scalper showing the relationship of the parts thereof.

Figure 2 is a section taken at right angles to the section line of Figure 1, the position of the section being indicated by the line 2—2 of 30 Figure 1.

Figure 3 is an enlarged detailed view showing a seal which prevents the grain and foreign material from passing over the ends of the rotating cylinder.

Figure 4 is an enlarged detail view showing the manner in which the inlet of the scalper may be regulated.

Figure 5 is a perspective view of a portion of the inlet regulating means shown in Figure 4.

Figure 6 is a plan view showing a portion of 40 the screen.

The scalper A is supported by four rectangularly arranged vertical angle iron legs 10 which are connected at their lower extremity by a 45 rectangular angle iron frame 11. A similar rectangular angle iron frame 12 connects the legs 10 at their upper extremity thereof. This angle iron frame extends approximately one-half the height of the scalper.

50 A pair of connecting hoppers or chutes are provided within the frame work above described. The main hopper 13 is centrally located between the end legs 10 as illustrated in Figure 1 of the drawings. The outlet aperture 14 of the hopper 55 13 may, however, be off-set transversely of the

machine if desired, as illustrated in Figure 2 of the drawings. The hopper 13 is provided along three of its four substantially rectangularly arranged upper edges by an outwardly extending end flange 15 and outwardly extending side flanges 16. The flanges 15 and 16 rest upon the angle iron frame 12 and are secured thereto for support thereby.

The fourth edge 17 of the substantially rectangular top of the hopper 13 is connected to a second hopper or chute 19. The chute 19 is substantially smaller than the hopper 13 and is designed to receive foreign matter carried over the top of the cylindrical screen. The chute or hopper 19 is provided with a substantially rectangular upper end including a laterally extending end flange 20 and opposed laterally extending side flanges 21, all of which flanges overlie the angle iron frame 12 and are secured thereto. The fourth edge 23 of the substantially rectangular hopper top is connected to the edge 17 of the hopper 13 as best illustrated in Figure 1 of the drawings. Thus the entire area within the frame 12 leads to either one hopper 13 or the other 19.

Mounted upon opposite sides of the angle iron frame 12, I provide opposed bearings 24 which support a rotatable shaft 25. Upon this shaft 25 are arranged a pair of spaced spiders 26 and 27. A cylindrical screen 29 is supported by the spiders 26 and 27. The spiders are secured to the shaft for rotation therewith and the shaft 25 is rotated by any suitable source of power, not illustrated in the drawings.

The screen 29 is preferably formed as best illustrated in Figure 6 of the drawings. A series of rounded indentations 30 project outwardly from the surface of the screen and apertures 31 are punched or otherwise formed in the indentations off-set from the center thereof. The apertures are so arranged in their indentations that one edge thereof is substantially flush with the cylindrical surface of the screen 29, while the other end thereof is at the top of the indentation. The apertures are so formed that their centers are in a diagonal direction from the direction of travel of the screen, as best illustrated in Figure 6 of the drawings. The lower edges of the indentations thus act as scoops to facilitate the entry of grain thereto and the position of the apertures seems to have an unusual effect in twisting the kernels of grain so that they may readily enter the apertures. These projections also increase the friction with which the large particles of foreign material engage the screen and facilitate the action of the screen in carrying these foreign materials over the top of the screen.

In order to guide any materials carried over the top of the screen into the chute 19, I provide a baffle plate 32 secured to the edges 17 and 23 of the hoppers 13 and 19 respectively. This baffle plate extends upwardly and toward the surface of the screen 29. A sealing band 33 of any suitable soft flexible material is secured to the baffle plate 32 and extends into contact with the surface of the screen 29, thus preventing any of the foreign particles from being carried past the baffle plate by rotation of the cylindrical screen.

An enclosure covers the cylindrical screen 29 as best illustrated in Figures 1 and 2 of the drawings. This enclosure follows to some extent the contour of the cylinder at the outlet end of the machine and forms an inlet hopper at the inlet end of the machine. The enclosure includes a

curved plate 34 which is provided with an end flange 35 secured to overlie the end flange 20 of the hopper 19. The plate 34 curves upwardly over the top of the screen 29 and terminates in a horizontal portion 36 which is bent upwardly at 37 and laterally at 38 to form a hopper flange. The plate 34 is provided with inwardly extending flanges 40 and 41. These flanges 40 and 41 extend throughout the length of the curved and horizontal portions of the plate 34 and form the sides of the inlet hopper 42. Where the flanges 40 and 41 extend upwardly to form the inlet hopper 42, the upper extremity of the flanges are bent laterally at 43 and 44 to form attaching flanges 15 coplaner with the flange 39. The housing of the scalper also includes an inclined end plate 45 which terminates at its upper extremity in a lateral flange 46 coplaner with the flanges 39, 43, and 44 and which extends downwardly toward the surface of the screen 29 terminating in a horizontally extending table or shelf 47. A flexible sealing member 49 of any suitable material is supported by the shelf 47 and engages against the screen 29 forming a seal to prevent grain and foreign particles from dropping between the surface of the screen 29 and the shelf 47.

Outer housing elements 50 and 51 are provided with top and curved flanges 52 and 53 respectively which overlap the side edges of the curved plate 34. These housing members 50 and 51 are likewise provided with parallel side walls 54 and 55 which extend down against the flanges 16, 20, and 24 overlying the frame 12. The purpose of the housing members 50 and 51 is to enclose the ends of the screen 29, to prevent the escape of any grain which passes through the screen and to provide an enclosure so that the aspiration of the grain may be controlled.

An inspection door 56 is provided in the plate 34. This door 56 is hinged at 57 and may be opened to inspect the work being done by the scalper.

An aperture 58 is provided in the horizontally extending portion 36 of the plate 34. A coupling 60 is secured in registry with this aperture 59 and a pipe opening 61 is provided at the top of the coupling through which air may be removed. The coupling 60 is connected to an air conduit which draws air upwardly from the body of the scalper, the air being conveyed carrying no chaff or straw, but other light particles such as dust.

In order to confine the grain and other material to the surface of the screen I provide a band 62 encircling each of the spiders 26 and 27. A circumferential flange 63 is secured to each band 62 to extend outwardly from the surface of the screen 29. The flanges 40 and 41 of the plate 34 extend in substantially coplaner relation with the flange 63, the flanges 40 and 41 being cut along an arcuate path so as to terminate outwardly of the flange 63. A pair of baffle plates 64 are bolted to each flange 40 and 41 as illustrated in Figure 3 of the drawings, these baffles having an off-set arcuate end 65 extending in overlapping spaced relation with the flange 63. Sealing pads 66 are secured between each of the off-set ends 65 of the baffle 64 and the flange 63, thus forming an effective seal to prevent grain or foreign material from sliding off the end of the rotatable cylinder.

In order that the inlet of the scalper may be regulated I provide a door or gate 67 secured to a transverse pivot shaft 68 in the inlet hopper. The shaft 68 is positioned adjacent the plate 36 defining one side of the opening while the free

edge 70 of the gate 67 may contact the end wall 45 of the housing.

An arm 71 having a slotted end 72 is secured to the shaft 69 to rotate therewith. A cross head 73 is threaded at 74 to accommodate an adjustment shaft 75 supported by a bearing 76. An adjustment seal 77 is mounted externally of the casing upon the shaft 75 by means of which the shaft may be rotated in its bearing. The shaft 75 is held from axial movement in its bearing by means of a collar 78 and nut 80. However, rotation of the threaded shaft 75 acts to move the cross head 73 longitudinally of the shaft.

The cross head 73 is provided with a bifurcated end 83 between the spaced portions of which the arm 71 extends as best shown in Figure 5 of the drawings. A pivot 81 extends through the bifurcated end 83 of the cross head 73 and through the slot 72 of the arm 71. Thus as the cross head 73 is moved longitudinally by rotation of the shaft 75, the gate 67 will be pivoted into open or closed position.

The operation of my scalper is believed obvious from the foregoing description. The grain is fed in through the adjustable gate 67 and slides down the inclined wall 45 building up a bank of grain on the shelf 47. The grain contacts the surface of the screen 29, some of the kernels of grain passing through the screen and others of the kernels being guided into subsequent openings through the screen. Impurities in the grain are brought into contact with the surface of the cylinder. The roughened cylindrical surface frictionally engages these particles and carries them over the top of the cylinder allowing them to fall into the chute or hopper 19.

The grain which falls through the screen 29 drops into the interior of the screen. This grain can either pass out through the openings in the bottom of the screen or when sufficient grain is built up within the cylinder the grain may fall through the opening in the spiders 26 and 27. All grain dropping through the cylinder or through the ends thereof is allowed to drop into the hopper 13 where it is discharged through the aperture 14.

During this operation dust is removed from the casing by suction. The air within the casing is partially evacuated, thus preventing the dust from being exuded from the machine.

In accordance with the patent statutes, I have described the principles of construction and operation of my horizontal rotary scalper, and while I have endeavored to set forth the best embodiment thereof, I desire to have it understood that obvious changes may be made within the scope of the following claim without departing from the spirit of my invention.

I claim:

- 10 A rotary scalper including a frame, a cylindrical screen, a shaft supported by said frame, spaced open spiders on said shaft for supporting said screen for rotation about a horizontal axis, a seal engaging against the screen on opposite sides thereof, an enclosure for said screen, a pair of baffles on said enclosure extending into close proximity with the upper portion of the screens between said seals, flange means on the screen near the ends thereof and arranged in overlapping relation with the baffle means, means for rotating said screen, one of said seals acting as a grain support and the other of the seals acting to strip from the surface of the screen material carried thereby, and a hopper beneath said screen to receive material passing through said screen, said hopper enclosing the lower portions of the ends of said screen and spaced therefrom to receive material passing through said spiders.
